COMPENSATING FOR DISTORTION IN TRANSMISSION

Application filed April 24, 1930, Serial No. 446,887, and in Great Britain July 10, 1929.

It is well known that in an ordinary telephone transmission system, frequencies are propagated at different rates so that means are usually provided for compensating for the unequal transmission times in order that faithful reproduction of the messages may be made at the receiving end. This invention relates to a telephone transmission system in which such means or phase compensators are provided.

In the employment of phase compensating networks it is desirable for reasons of economy to use the minimum number possible for a given degree of compensation and for quality reasons to insure that as far as possible the proper termination of the networks is provided. Also the networks will not give the value of delay for which they are designed unless perfectly terminated.

According to one feature of the present invention a circuit arrangement comprises two sections each of which consists of two transmission paths, one for one direction and the other for the opposite direction, a phase compensating network being situated in an intermediate path joining said sections and adapted for transmission in both directions.

According to another feature of the invention in a transmission line employing a repeater of the two wire type, there is provided at a repeater point an additional repeater or an impedance matching network, between which and the normal repeater is situated a phase compensating network and/or attenuation equalizer. Other features of the invention will be disclosed in the following description in which Figure 1 illustrates a four wire system modified in accordance with the present invention and Figure 2 illustrates a two wire circuit embodying the principles of the invention.

In the first figure, 1, 2, 3, 4 are four one way amplifiers. 5 and 6 are two hybrid coils or three winding transformers and may be replaced by any suitable known bridge arrangement. 7 is a detector amplifier operating relay systems 9 and 10, which at appropriate times render inoperative the east incoming (EI) circuit and the west outgoing (WO) circuit. Similarly 8 is a detector amplifier

operating relay systems 11 and 12 which at appropriate times render inoperative the west incoming (WI) circuit and the east outgoing (EO) circuit. 7, 8, 9, 10, 11 and 12 may be replaced by any suitable known echo suppressors. 13 is the phase compensating network which, as is now evident, is traversed by speech currents travelling either from east to west or from west to east and therefore affords phase compensation for conversations in both directions. If necessary, to permit 7 and 9 to operate before unbalance currents starting from 1 arrive at 9, a network 14 giving a small constant delay may be inserted between 5 and 9; similarly a delay network 15 may be inserted between 6 and 11. In practice it is probable that these networks will not be necessary, since the major part of any unbalance currents traversing the hybrid coils will be delayed through having traversed a part or the whole of network 13. The positions in which these networks 14 and 15 are shown are their preferred positions, notwithstanding the fact that this positioning requires twice as many sections of delay networks as would be required were these networks positioned one at each end of network 13; for the latter positioning would require that, for these networks 14 and 15 to fulfill their function, they give a better balance against the balancing resistance than does the delay network proper.

It is evident that the same result can be achieved whether the two wire portion of the circuit in which the network 13 is located is situated at any point in the middle of the four wire circuit or at its ends. An economic arrangement is provided by locating the network 13 and its associated apparatus at the point in the four wire circuit where the echo suppressors normally associated with the four wire circuit are situated. In such case these echo suppressors are represented by 7, 8, 9, 10, 11 and 12. Echo suppressors can evidently be disposed in different parts of the circuit to perform the same function without departing from the spirit of the invention.

The method of operation of the system is symmetrical and consideration of a conver-

sation from west to east will be sufficient to explain the working of the whole system. Speech arriving from the circuit WI passes through the amplifier 1 and operating relay 5 systems 9 and 10 through the detector amplifier 7 paralyzes circuit WO and EI. The speech then proceeds via the hybrid coil 5. The compensating network 13, hybrid coil 6 and amplifier 3 to the circuit EO. The relay system 9 is intended to prevent unbalance speech currents originating from WI passing through the hybrid coil 5 and returning via WO and giving rise to talker echoes. Practically the balance of the hybrid 10 coil to instantaneous transients will be very high and any currents arriving at 9 from WI will be delayed by having traversed the whole or part of network 13 twice as a result of reflection from irregularities. For this reason the relay system 9 will in practice have ample time to operate before any echo currents reach 2. The relay system 10 will also have ample time to operate since the echo path between amplifier 1 and this point includes the delay network 13 and the return circuit from the EO and EI. It is evident that where other types of distortion are to be corrected, such as unequal attenuation of different frequencies, the same arrangement 20 can be used with advantage, attenuating correcting networks being inserted in place of or in association with the phase compensating network 13.

In Figure 2 is illustrated a two wire circuit which has been modified in accordance with the principle of the present invention.

Compensating networks of the type which are normally employed must be terminated in their characteristic impedance in order 40 that the optimum results may be obtained.

The type of cable circuits normally employed have a characteristic impedance which varies with frequency, whereas the type of phase compensating networks have an impedance which is substantially independent of frequency. For this reason it is not convenient to connect phase compensating networks directly in series with the cable circuit.

In Figure 2 this is avoided by the addition of an extra repeater, or alternatively, of any other suitable type of impedance matching network, in circuit at the point where a two wire repeater is normally inserted in the line. The phase compensating networks are then inserted between the normal repeater and the second repeater or other impedance matching network. An alternative is the provision of two of the latter impedance matching networks in the circuit, at any suitable point, between which the phase compensating networks are placed.

22 is the ordinary two wire repeater inserted between lines 17 and 18. It comprises the amplifiers R_1 and R_2 . A phase compen-

sating network 24 has been added in the circuit for the purpose of compensating the different times of transmission of the telephone frequencies over the line 17, 18. In order that a correct matching of impedance of the compensating network 24 may be made on both sides a second two wire repeater 23 has been inserted as shown comprising amplifiers R_3 and R_4 . If desired the repeater 23 may be substituted by an impedance matching network which would simulate very closely the impedance of the repeater. Thus in the arrangement shown, the balancing network 19 may be designed to give proper termination to the compensating network 24 and in similar manner the value of the balancing network 20 would be determined, and the impedance presented by the repeaters towards the phase compensating network should then be substantially a pure resistance independent of frequency. On repeatered circuits where echo suppressors are employed it may be advantageous to locate the phase compensating networks at the same point as the echo suppressors so that undesirable echoes may be eliminated. It is evident that similar arrangements may be employed where constant resistance attenuation equalizers are required to be used on two wire circuits, the equalizers may then be placed in the same position as the phase compensating networks.

In the two wire case (i. e. Fig. 2) if the balance of the lines 17 and 18 against their respective networks is very poor the impedances presented to the network 24 may depart from a pure resistance. In such case intolerable departures from the desired delay characteristic may be obviated by the use of resistance pads 25 and 26 inserted between 24 and the hybrid coils on each side of it.

What is claimed is:

1. A telephone transmission system comprising two sections with adjacent terminals, each section consisting of two transmission paths, one for one direction and the other for the opposite direction of transmission, and, joining said sections, an intermediate path for transmission in both directions, a phase compensating network being situated in said intermediate path.
2. A four wire telephone transmission circuit comprising, in combination, two sections with adjacent terminals, each section consisting of two transmission paths, one for one direction and the other for the opposite direction of transmission, and, joining said sections, an intermediate path for transmission in both directions, a distortion correcting network being situated in said intermediate path.
3. A telephone transmission system comprising two sections with adjacent terminals, each section consisting of two transmission paths, one for one direction and the other for the opposite direction of transmission,

and, joining said sections, an intermediate path for transmission in both directions, an attenuation equalizer being inserted in said intermediate path.

4. The combination with a telephone transmission line of the two way, two wire type, of a distortion correcting network and two two-way repeaters at the same point in said line, said repeaters connecting said distortion correcting network therebetween in said line.

5. The combination with a telephone transmission circuit of the two way, two wire type having a characteristic impedance which varies with frequency, of a phase compensating network having an impedance which is substantially independent of frequency, and two two-way repeaters at the same point in said line, said repeaters connecting said phase compensating network therebetween in said line.

6. A four wire circuit according to claim 2, comprising a group of echo suppressors near the middle of the four wire circuit, said distortion correcting network being located at said group of echo suppressors, with certain of the suppressors at one side of the network and certain of the suppressors at the other side of the network.

In witness whereof, we hereunto subscribe our names this second day of April, 1930.
